UNITED STATES PATENT OFFICE.

RALPH M. BURDICK, OF LOS ANGELES, CALIFORNIA.

PISTON.

Application filed May 9, 1922. Serial No. 559,508.

To all whom it may concern:

Be it known that I, RALPH M. BURDICK, a citizen of the United States, residing at Los Angeles, in the county of Los Angeles and State of California, have invented new and useful Improvements in Pistons, of which the following is a detailed specification.

This invention relates to pistons for any kind of piston and cylinder mechanism; and although the piston has been designed particularly with internal combustion engines in view it will be understood that the invention is not at all limited to use in an internal combustion engine.

There are certain difficulties attendant the use of cast iron pistons in high speed engines; one of the primary disadvantages being the weight of the piston which causes undue vibration and necessitates careful building of the parts in order to reduce such vibration. Cast iron pistons in order to be made of light weight must be made very thin and are liable to breakage. On the other hand pistons of aluminum or aluminum alloys, although light, have a coefficient of expansion greater than cast iron and consequently when fitted into cast iron cylinders must be made somewhat small so that they will not bind when the average working temperature is reached. This of course, necessitates a certain looseness at lower temperatures, causing the pistons to slap and allowing excessive oil to work up into the combustion chamber, necessitating in turn the frequent cleaning of spark plugs.

This invention has for a general object the provision of a piston which has the desirable features of both the cast iron piston and the alloy piston, with none of their disadvantages. This and other objects and corresponding features of the invention will be best understood from the following detailed description of preferred forms of the invention, reference for this purpose being had to the accompanying drawings in which:—

Fig. 1 is a longitudinal central section of one form of my improved system; Fig. 2 is a similar view of another form; and, Fig. 3 is a similar view of another form.

In making my piston I provide a piston body with a head 10 and side walls 11 and with the usual wrist-pin bearings 12, and with whatever ribbed reinforcement 13 may be necessary or desirable to strengthen the piston. Although I illustrate the piston

body here as having tapering side walls which taper from the head to the skirt end of the piston but it will be readily understood that the invention to which this application is particularly directed is applicable to any form of piston structure proper. The tapering walled structure has certain advantages in the radiation and conduction of heat from the piston; but this subject matter is to be covered by a co-pending application.

In the cylindrical piston wall I set one or more cast iron bands as illustrated, in the various form of the device, at 14, 14^a and 15. For instance, in Fig. 1 there is illustrated a cast iron band 14 that is put into place after both the piston body and the band have been machined by shrinking the band onto the piston body in the well known manner. Thus in this case the band 14 is at or near the upper end of the piston, its edge being shown in the drawings as flush with the head surface of the piston. The exterior cylindrical surface of band 14 is substantially the same as or may be slightly greater or lesser in diameter than the diameter of the piston body at that point. If larger, or of the same size it may be used as a wearing surface. This external diameter of the band is made with substantially the clearance used for cast iron pistons. And this band carries the piston rings 16 of any suitable number and any suitable construction. The band is heavy enough that the interior expansion of the aluminum or alloy piston body will not break the band and will not cause the band to expand much more than at its normal expansion rate. Of course, it is inevitable that, due to the differential rate of expansion between the two metals, the band will be resiliently expanded slightly over and above its normal heat expansion rate; but the strength of the band is so designed that the major portion, or at least a large portion, of the difference in expansion is taken up by compression of the piston body.

When I say that the band is made of cast iron I mean merely to specify a suitable material. Other materials of about the same rate of expansion as cast iron may be used, and which will give a good wearing engagement with the cylinder. For instance, certain types of steel may be used for the band; and in selecting the material for the band it may be preferred to select one that has a co-efficient of expansion

slightly less than that of cast iron; so that the ultimate expansion of the band, due to heat and due also to the larger expansion of the encircled piston body, will cause the band to expand at the same rate, or at substantially the same rate as the cast iron cylinder. Furthermore, it will be understood that I am giving this description on the assumption that cylinders are made of cast iron. They are now commonly so made. But in a cylinder made of any other material, or containing a piston surrounding sleeve of any other material, the material of the band will be modified accordingly to make that band either of the same material or of a material having the same or substantially the same coefficient of expansion, or a slightly lesser coefficient of expansion, as herein set forth.

In Figs. 2 and 3 I illustrate another structure which embodies the same ideas hereinabove set forth. In these cases, however, the band 14^a is set at a little distance from the head surface of the piston. To form this structure the band is first made and machined and then pressed in the mold in which the piston body is cast, and the piston body is cast directly in the band. The whole exterior surface may then be accurately machined, the exterior surface of the band being machined concentric with the exterior surface of the piston and projecting slightly above the piston surface.

In Fig. 2 I also show a similar construction applied at the skirt end of the piston; where a band 15 is also set in the piston body carrying a ring 17. This band 15 may be, in normal cases, a relatively narrow one carrying a single ring; but it will be understood that any of these bands herein described may be made of any desired width to carry any number of rings.

From the foregoing description and the illustrations herein given I believe my invention will be made clear. It will be understood however that these illustrations are not given for the purpose of necessarily limiting the invention to their specific details, but are given for the purpose of making the whole of my invention clear and plain to those skilled in the art. Accordingly, I do not limit the invention except as set out in the following claims.

Having described a preferred form of my invention I claim:

1. A piston for a cylinder, the piston including a piston body of a material having a coefficient of expansion greater than the material of the cylinder, and a ring carrying band surrounding the piston and composed of a material having a coefficient of expansion slightly less than the coefficient of expansion of the cylinder material so that the expansive forces of the encircled piston body causes the band to expand substantially at the same rate as the cylinder.

2. A piston for a cylinder, the piston including a piston body of a material having a coefficient of expansion greater than the material of the cylinder, and a cylinder bearing band surrounding the piston with its outer cylindrical surface slightly above the outer cylindrical surface of the piston and composed of a material having a coefficient of expansion slightly less than the coefficient of expansion of the cylinder material so that the expansive forces of the encircled piston body causes the band to expand substantially at the same rate as the cylinder.

3. A piston for a cylinder, the piston including a piston body of aluminum-like material having a coefficient of expansion greater than the material of the cylinder, a cylinder bearing band encircling the piston body with its outer cylindrical surface projecting slightly beyond the outer cylindrical surface of the body, piston rings carried in said band; and said band being composed of a material having a coefficient of expansion slightly less than that of the cylinder material, so that the greater heat expansion of the encircled piston body causes the band to expand substantially at the same rate as the cylinder.

4. A piston for a cylinder, said piston including a body of suitable material, and a band encircling the piston and formed of a material having a coefficient of expansion slightly less than the coefficient of expansion of the cylinder material.

In witness that I claim the foregoing I have hereunto subscribed my name this 27th day of April, 1922.

RALPH M. BURDICK.
